UNITED STATES PATENT OFFICE.

CHARLES S. WHEELWRIGHT, OF BRISTOL, RHODE ISLAND.

GARBAGE AND RENDERING APPARATUS.

No. 925,970.

Specification of Letters Patent.

Patented June 22, 1909.

Application filed September 26, 1908. Serial No. 454,904.

To all whom it may concern:

Be it known that I, CHARLES S. WHEELWRIGHT, a citizen of the United States, and residing at Bristol, in the county of Bristol 5 and State of Rhode Island, have invented certain new and useful Improvements in Garbage and Rendering Apparatus, of which the following is a specification.

This invention has been made with especial reference to the connection or passageway between digesters and extractors used in what may be termed the hot water process in removing oil from tankage in garbage and rendering plants. An example of the 15 extractor with a full description of its construction and mode of operation will be found in my Patents No. 783,602, dated February 28, 1905, and No. 890,112, dated June 9, 1908. In the last named patent is 20 shown a casting forming the inlet to the extractor adapted to be secured to a casting forming the outlet of a digester. A general description of the construction and mode of operation of the digester used in carrying 25 out the present invention will be found in my Patent No. 774,804, dated November 15, 1904, except that the conical bottom of the digester and the interior wall of the outlet thereto and the interior wall of the inlet 30 to the extractor are in line as shown in the drawings herewith annexed.

The invention herein described is in furtherance of a continued process of which the digester and extractor perform but portions, and is designed to obviate the necessity for disconnecting the digester from the rest of the apparatus by which the entire apparatus is worked. It happens not unfrequently that the outlet to the digester or 40 the inlet to the extractor becomes clogged with rags or similar substances so that tankage will not pass to the extractor, whereby the entire apparatus is held up it may be for hours. Accordingly, one part of my invention consists in means for obviating said difficulty and embodies the combination with the digester of means adapted to force the contents of said passageway through the 45 passageway. I employ in combination with the digester and extractor a steam ram adapted to work along the conical bottom of

the digester into the passageway connecting the digester and extractor. It so happens, however, that as shown in said former patent 890,112 there is already working across 55 said passageway a steam valve gate or knife substantially at right angles to the path of the ram, and thus it has become necessary to provide means whereby the said devices shall not interfere with each other in their 60 operations, and an essential part of my invention consists of means whereby either ram or valve gate may perform its office separately, without interfering with one another, or both may be withheld from operating. 65

In the drawings: Figure 1 is a view of so much of a digester and extractor as is contained in the present invention, including the ram and the valve gate and means 70 for operating both. Fig. 2 is an enlarged view of the ram showing more fully the construction thereof and its connection with a steam cylinder by which it may be operated, independently of devices for operating 75 the valve gate. Fig. 3 shows the ram at right angles to the view of the same shown in Fig. 2; Fig. 4 is a cross-section of the ram on the line 4—4 of Fig. 3.

A is the digester. A' is the lower or conical 80 section thereof. A² is the mouth of the digester. B is one of the supports of the digester, a flange A³ from the digester resting on said support. With these parts is combined means whereby in the normal or regular 85 operation of the machine the material is caused to positively flow through the digester to the outlet. As shown such means consist in a rotating screw E within a suitable casing, coacting with one by which the material is fed to the upper end of the digester as set forth in my aforesaid Letters Patent. P⁵ is a passageway between the digester and extractor consisting of several 90 strong castings across one of which operates a valve gate V⁵ by means of a piston T' in a steam cylinder S, as appears in my said Patent No. 890,112, and as will more fully appear herein.

The ram and operative parts (see Fig. 2) 100 will first be described. C² is a bracket secured to the digester by bolts c, c. D is an

opening near the top of said conical section A' at one side closed by a cover E³ bolted to the sides of said opening by bolts c', c'. The said cover is provided with a stuffing box F in and through which works a piston rod t⁴ which is formed in two parts, 1 and 2, and which is provided with a joint or hinge H. The part 2, at its lower end is cast with a projection or swelling 3, which increases in size, as shown, to the middle portion thereof, whence it tapers to near a point at the extreme end. One side of the projecting portion 3 of the piston rod is curved, as shown, to conform to the round shape of the 15 conical bottom of the digester, (see Fig. 4). The upper end of said piston rod is secured to the piston T² having a reciprocating motion in a steam cylinder S² accordingly as steam is admitted to one side or the other of 20 the piston, as hereafter described. The cylinder S² is provided with cylinder heads N, N', buffers P, P, and stuffing box F' in the usual manner, and is held in a support R, cast upon the end of curved bracket C², before mentioned. The bracket C² is of such 25 shape that the steam cylinder S² lies in a continuation of the line of the conical bottom of the digester and the exit pipe P⁵, so that the piston rod t⁴ may normally work 30 close to the wall of the digester. The piston rod t⁴ as before stated, is provided with a hinge H which is formed, as shown at Fig. 3, by a bolt l' passing through forked projections t', t' from part 2 of the piston rod and 35 a tongue t² from part 1 of the piston rod, the said tongue t² being rigidly secured to said part 1 by a wedge w passing through a hole near the end of said part 1 and corresponding holes in a cup on the end of the 40 tongue t². The bolt l' and wedge w are secured in their respective positions by cotter pins y', y².

While I have found that a ram and actuating devices for carrying it to and from the 45 discharge opening is effective, I do not limit myself to the use of a ram since any other suitable means for clearing the discharge opening as required would embody this feature of my invention.

50 The part of the invention consisting in means whereby either the ram or the valve gate must perform its office separately, or both be withheld from operating, will be best understood from a description of the 55 mode of operation of certain steam cylinders, pistons, piston rods, valves, and steam passageways governing the movements of said ram and said valve-gate, as illustrated in the drawing at Fig. 1, where the valve 60 gate V³ is shown as across the passageway P⁵ that being the position of said gate as shown in my said Patent No. 890,112, to which position it has been carried by steam entering the steam cylinder S', as will be de-

scribed, and exerting its force upon one side 65 of pistons T'. [In the drawings but a single cylinder and piston are shown but in practice there are two cylinders with pistons one on each side of said passageway P⁵, the two piston rods being connected by a yoke Y to which the gate is attached.] Steam is supposed to be on at pipe P' and to have forced valve V' to its seat e thereby cutting off communication between pipe P' and pipe P⁹ leading to cylinder S², which is used as 70 before stated in connection with the ram. The valve V' has a stem working through its said seat e into the interior of said cylinder S¹, being furnished with suitable packing. So, too, steam is on at main entrance 75 pipe P² but valve V² is off its seat, having been pushed up by pressure of the nut on piston rod t⁴ upon valve stem t⁶ carried by valve V² and a passage is made for steam 80 from main entrance pipe P² through pipe P⁶ leading to valve cock O' which has been so turned by hand lever R' as to admit steam 85 from pipe P⁶ through bent pipe P³ to one side of piston T' thereby forcing the said piston T' to the bottom of cylinder S', carrying with it the valve gate V³ across the 90 entrance passage P⁵, the position shown in the drawings. (It may be assumed that entrance pipe P' and entrance pipe P² are supplied with steam from the same source.) 95

A study of the steam pipe connections of the apparatus will show that while the piston T' is thus held at the end of its cylinder S' in turn holding the valve gate V³ across the passageway P⁵, in no possible way can 100 steam be admitted by valve cock O² to cylinder S² to force piston T² toward the end of its cylinder next the digester and carry the ram operated by said piston T² down into the passageway P⁵ across the path of said 105 valve gate V³. But if lever R' operating valve cock O' be now turned by hand so that steam coming through pipe P⁶ will be diverted through pipe P⁷ to the other side of piston T', causing said piston to travel to the 110 other end of cylinder S' and thus withdrawing the valve gate from across said passageway P⁵, the said piston in its travel to the said other end of cylinder S' will cause its piston rod to press against valve stem t, lifting 115 valve V' from its seat, thus offering a passage for steam from entrance pipe P' through pipe P⁹ to valve cock O² which may be so turned by lever R² as to admit steam 120 through bent pipe P⁸ to the upper side of piston T² and send that piston down the digester carrying the ram into the said passageway P⁵. And while the ram is thus in the said passageway the gate will be prevented from crossing the said passageway 125 for reasons similar to the reasons which kept back the ram while the gate was closed.

By manipulating the hand levers R' and

R² both the valve gate and the ram can be withheld from closing or entering the passageway P⁵, but said hand levers R' and R² cannot be so operated that the valve gate and 5 ram shall simultaneously cross the path each of the other.

Having thus described the invention, what is claimed is:

1. The combination with a digester having 10 a discharge opening at the lower end, of supplemental means within said digester movable to and from the discharge opening and adapted to act on material clogging said opening to push said material through said 15 opening, and actuating devices without said digester adapted to operate said means within said digester.
2. The combination with a digester having 20 a discharge opening at the lower end of a ram within said digester adapted to move down into and back from said opening, and actuating means for moving said ram whereby the said ram is the means of positively 25 and directly pushing any obstruction through the discharge opening.

3. The combination with a digester having 30 a discharge passage leading from the lower portion thereof to a vessel or chamber adapted to the further treatment of the material 35 cooked in said digester and discharged therefrom through said passageway, of means arranged to act on material within said passageway and push it longitudinally in a direct line through the same.

4. The combination of a digester having 40 a discharge passageway leading from the lower portion thereof to a vessel or chamber adapted to the further treatment of the material 45 cooked in said digester and discharged therefrom through said passageway, of means arranged to act on material within said passageway and push it longitudinally through the same, and actuating devices for operating said means.

5. The combination of a digester having 50 a discharge passageway leading from the lower portion thereof to a vessel or chamber adapted to the further treatment of the material 55 cooked in said digester and discharged therefrom, the said passageway having therein a gate adapted to close said passageway, with devices for positively and instantaneously operating said gate and means adapted to act upon said material in said 60 passageway and push it through said passageway when the said gate is open.

6. The combination of a digester having 65 a discharge passageway leading from the lower portion thereof to a vessel or chamber adapted to the further treatment of the material 70 cooked in said digester and discharged therefrom, the said passageway having therein a gate adapted to close said passageway, with means for instantaneously oper-

ating said gate and means adapted to act 65 upon said material in said passageway and force it through said passageway, the arrangement of said means being such that either is prevented from operating when the other has operated, and that both can 70 be prevented at any time from operating.

7. The combination with a digester such as is employed for cooking garbage and articles of similar nature, provided with a conical bottom end and with a discharge opening 75 at said end, of a steam ram, and means to reciprocate it parallel to the said bottom to and from said opening.

8. The combination with a digester having a tapering bottom with an opening at 80 the point, of a ram within said digester adapted to move down said tapering bottom into said opening to push obstructions through said opening, a fluid operated piston outside of said digester, and means extending through the wall of said digester for 85 operating said ram from the piston.

9. The combination with a digester such as is employed for cooking garbage and articles of similar nature, provided with a 90 conical section at the lower end, of a steam ram adapted to work along the bottom of said conical section against articles in the mouth of the digester, the said ram being made tapering to a point. 95

10. The combination with a digester having a tapering bottom with an opening on one side at the point, of a ram within said digester adapted to move down said tapering bottom into said opening, a fluid operated piston secured to said digester above the top of the tapering portion in line with the ram and opening, and a piston rod extending through the wall of the digester and secured to said ram. 100

11. The combination with a digester having a tapering bottom with an opening at the point, of a ram within said digester means for reciprocating said ram to and from said opening whereby it can operate to push obstructions through said opening, a fluid operated piston outside of said digester, a piston rod extending from said piston into the digester, and hinged connection between said piston rod and ram. 110

12. The combination with a digester having a tapering bottom with a discharge opening in one side at the point, of a bracket secured to the digester at the side opposite the opening, a fluid operated piston secured to said bracket parallel with and immediately above the upper end of the tapering bottom, a piston rod extending through an opening in the wall of said digester, a stuffing box for said piston rod, and a ram with in the digester secured to said piston rod and adapted to enter said discharge opening. 120

13. The combination with a digester such

as employed for cooking garbage and articles of similar nature, provided with a conical section at the lower end, of a steam ram adapted to work along the bottom of said 5 conical section against articles in the mouth of the digester, the said ram having an under surface of such shape as to fit the wall of the conical section and being pro-

vided on its upper surface with an enlargement tapering toward the ends. 10

In testimony whereof I affix my signature in presence of two witnesses.

CHARLES S. WHEELWRIGHT.
